US0D1072269S

(12) **United States Design Patent** (10) Patent No.: **US D1,072,269 S**
(45) Date of Patent: ** Apr. 22, 2025

(54) **LABORATORY ANALYSIS APPARATUS**

(71) Applicant: **Lightcast Discovery Ltd**, Cambridge (GB)

(72) Inventors: **Benedict Pemberton**, Cambridge (GB); **Bruce Hutchison**, Cambridge (GB); **Alasdair Barnett**, Cambridge (GB)

(73) Assignee: **LIGHTCAST DISCOVERY LTD.**, Cambridge (GB)

(**) Term: **15 Years**

(21) Appl. No.: **35/518,065**

(22) Filed: **Apr. 18, 2023**

(80) **Hague Agreement Data**

Int. Filing Date: **Apr. 18, 2023**
Int. Reg. No.: **DM/230662**
Int. Reg. Date: **Apr. 18, 2023**
Int. Reg. Pub. Date: **Aug. 11, 2023**

(30) **Foreign Application Priority Data**

Oct. 19, 2022 (GB) 6237928
Oct. 19, 2022 (GB) 6237929

(51) **LOC (15) Cl.** **24-02**

(52) **U.S. Cl.**

USPC **D24/216**

(58) **Field of Classification Search**

(57) **CLAIM**

The ornamental design for a laboratory analysis apparatus as shown and described.

DESCRIPTION

1. Laboratory analysis apparatus
- 1.1: Top Front Left Perspective
- 1.2: Top Front Right Perspective
- 1.3: Top View
- 1.4: Right View
- 1.5: Rear View
- 1.6: Left View
- 1.7: Front View
- 1.8: Top Rear Right Perspective
- 1.9: Top Rear Left Perspective
- 1.10: Bottom View

1 Claim, 10 Drawing Sheets
